UNITED STATES PATENT OFFICE.

HORACE GRAY, OF BOSTON, MASSACHUSETTS.

LOCOMOTIVE-ENGINE.

Specification of Letters Patent No. 17,213, dated May 5, 1857.

To all whom it may concern:

Be it known that I, HORACE GRAY, of Boston, in the State of Massachusetts, have invented a new and useful Improvement in 5 Locomotive-Engines for Railroads, of which the following is a full, clear, and exact description, reference being had to the accompanying drawings, making part of this specification, in which—

10 Figure 1, is an elevation partly in section of my improved plan; and Figs. 2, 3, and 4, are elevations of different modes of applying my said invention.

Serious difficulties have been experienced 15 in generating steam for locomotives, particularly with anthracite coal, the use of which is very desirable for many reasons if it could be applied as successfully and economically as it has been in boilers for stationary and steamboat engines.

As locomotive engines have heretofore been constructed the grate and fire surface must of necessity be very much contracted, and in consequence the intensity of the fire 25 in the furnace must be greatly increased which results in a waste of fuel and in the rapid deterioration of the furnace and parts of the boiler in the vicinity thereof. And not only is this a necessary consequence with 30 all kinds of fuel, but with anthracite coal other and more serious consequences result. To obtain the required evaporation from a limited extent of grate and fire surface by increasing the intensity of the fire the charge 35 of coal must be made of greater depth with an increased blast or draft to supply the increased demand for oxygen; from which two fatal consequences have resulted, viz— The tremulous motion and jars of the locomotive pack down the charge of coal to such 40 an extent as to greatly impede the draft or blast, and the heat becomes so intense at the grate bars and immediately above and around them that the coal soon slags and 45 runs together completely shutting out the draft and seriously injuring the furnace.

There are other objections to the present system not necessary to be enumerated as those above stated will be sufficient to enable 50 a competent engineer to appreciate the importance of my improvement, the object of which is to enable me to increase the grate and fire surface to any extent necessary to an economical application of fuel, and to 55 generate the steam of the quantity and tension desired by the extent of the grate and

fire surface with a moderate fire, instead of by a small extent of grate and fire surface and great intensity of fire. And with the view to the accomplishment of the important ends specified, my invention consists in constructing a locomotive steam engine with two or more separate boilers or with one boiler having two or more separate fire boxes or furnaces, placed on the tender or 60 on a separate carriage, and the steam chamber or chambers connected with the engine by a pipe or pipes having universal joints to admit of the required motions.

In the accompanying drawings (see Fig. 70 1) *a* represents the carriage of a locomotive engine of the usual construction with a pilot truck *b* in front, and two pairs of driving wheels *c*, *c* behind. Over or between the driving wheels I place a boiler *d* of any suitable construction and of sufficient weight to give the required adhesion to the driving wheels. I place the fire box *e*, with its grate *f* and other appendages at the rear end, and make the grate and fire surface of such 80 boiler of much greater proportional capacity than has heretofore been the practice in locomotive boilers, say of the proportional capacity best suited to the economical application of fuel, and without reference as 85 heretofore to compactness. This boiler is to communicate with the engine cylinders in the usual or any other convenient way.

On the forward part of the tender *g*, coupled with the locomotive, I place a second 90 boiler of any suitable construction, and of such capacity as to generate, in connection with the boiler on the engine, the required quantity of steam and at the desired tension to drive the engines. This boiler, however 95 it may be constructed, I make with the extent of grate and fire surface adapted to the economy of fuel and not with the view to compactness. I then connect the steam chambers of both boilers by means of a 100 pipe *h* with three ball and socket joints *i*, *i*, *i* of the usual construction, or by equivalent means, which will admit all the required play between the locomotive and the tender in starting and stopping and in 105 passing over the curvatures and irregularities of the road. By this arrangement it will be seen that any desired extent of grate and fire surface can be obtained to use any and all kinds of fuel with economy by extent of surface instead of intensity of heat.

The door of one furnace can be opened

to tend and feed the fire while the other is closed so that there will be less check to the generation of steam, and much greater facility will be presented for repair, while there will be much less tendency to wear and tear, particularly when burning anthracite coal.

Instead of the above arrangement I have contemplated the application of the principle of my invention according to the following modifications—viz: When great adhesion of the driving wheels is required I place the two boilers on one carriage as represented in Fig. 2 where *a* and *b* represent the two boilers, the steam chambers of which are connected by a pipe *c* there being a separate fire box or furnace for each boiler with the required extent of grate and furnace. But as the length occupied by two such boilers would of necessity be very great, the platform *d*, on which the boilers and engines are placed may be mounted on two four wheel trucks *e*, *e*, placed near the ends thereof and so connected as to swivel on the principle of the eight wheel car in general use. And the driving wheels *f*, *f*, which are connected with the engines *g* on the platform *d*, may be connected by suitable pedestals in the usual manner with the under part of the said platform. In such an arrangement the driving wheels should be without flanches, or the play between the flanches and the rails should be so great

that in passing around curves the whole structure will be guided by the flanches of the wheels of the trucks, the treads of the driving wheels being sufficiently wide to traverse laterally on the rails, or instead of the above the two boilers may be placed on a separate carriage as represented in Fig. 3, where *a* represents the locomotive engine, *b* the separate carriage, and *c*, *d*, the two boilers connected by a steam pipe *e*; the boiler *c* being in turn connected with the engine *a* by a pipe *f* with ball and socket or other equivalent flexible joint. Or instead, one large boiler with two separate fire boxes or furnaces may be placed on a separate carriage as represented in Fig. 4. And in either of the above modifications the separate carriage connected with the locomotive engine may be used as the tender also, or a separate tender may be connected therewith.

What I claim as my invention and desire to secure by Letters Patent is—

Constructing locomotive steam engines with two or more boilers, or with one boiler having two or more separate fire boxes or furnaces connected and operating on the principle and for the purpose substantially as herein specified.

HORACE GRAY.
